UNITED STATES PATENT OFFICE.

HIRAM C. STOUFFER, OF CORTLAND, OHIO, ASSIGNOR TO CARVER C. TROUT, OF SHARON, PENNSYLVANIA.

COMBINED LOCK-LATCH AND HASP.

SPECIFICATION forming part of Letters Patent No. 312,926, dated February 24, 1885.

Application filed June 12, 1884. (No model.)

to all whom it may concern:

Be it known that I, HIRAM C. STOUFFER, a citizen of the United States, residing at Cortland, in the county of Trumbull and State 5 of Ohio, have invented new and useful Improvements in Combined Lock-Latch and Hasp, of which the following is a specification.

The invention relates to devices which are 10 known as "hasp-locks," but my improvements are directed to the combination of a slotted latch-bar with a lock having spring-held tumblers and an independent latch-keeper bolt to lock the two, when required, and to 15 provide such an independent latch-keeper bolt as will answer the purpose of a combined lock and latch, with such functions made interchangeable, so as to dispense with padlocks.

The matters of improvement claimed are 20 hereinafter specifically described and ascertained with reference to the accompanying drawings, in which—

Figure 1 represents the device when attached to a gate or door, the lock portion thereof being secured to the jamb and the latch portion to the door. Fig. 2 is a side view when used as a latch; Fig. 3, a side view of the same when used as a lock; Fig. 4, a perspective view of the independent latch-keeper bolt. Figs. 5 and 6 are bottom and 25 end views representing the relative positions of the latch, bar, and independent latch-keeper bolt when the device is used as a latch. Figs. 7 and 8 are bottom and end views representing the relative positions of said parts 30 when the device is used as a lock. Fig. 9 represents the lock proper with its cap removed, showing the independent latch-keeper bolt retained by the tumblers, the arms of the 35 tumblers being broken away to show the action of the spring which ejects the latch-keeper bolt. Fig. 10 represents a similar view to show the manner in which the latch-keeper bolt is released from the tumblers by 40 the application of a key. Fig. 11 is a side view of a portion of the latch-bar; Fig. 12, a side view of the lock, latch-keeper bolt, and 45 a portion of the latch-bar; and Fig. 13 is an end view of the slotted latch-bar.

50 The gate or door is designated by the letter

A, and the post or jamb by the letter B, in Fig. 1. The lock-case C is provided with a screw-stem, r, by which it is secured to the post, as seen in Fig. 12, or it may be secured in any suitable way. The lock C, conforming to a known construction, has hooked pivoted tumblers b b and cam-arms c c, Fig. 10, formed or cast with said tumblers, which are actuated by a key, F, to release the latch-keeper bolt D, and which are caused to retain 60 said bolt D by the pressing force of side springs, b' b', as in Fig. 9.

It will be understood clearly from Fig. 9 in what manner the independent latch-keeper bolt D is held by the hooked tumblers b b, and 65 from Fig. 10 in what manner it is ejected by the spring m, pressing against the end of said bolt D when a key is applied to turn and open the tumblers.

Further description of the lock proper is 70 deemed unnecessary, as any suitable construction of lock may be used.

The latch-bar E is pivotally secured to the door and its movements controlled by the ordinary hasp, d, while it has also thumb-buttons 75 e e, connected for operation from the inside or outside by a stem, f, passing through a slot of the door or gate, as shown in Fig. 11. The latch-bar has a slot, g, as shown in Figs. 1, 2, and 3, of sufficient length between lock and 80 latch-hasp to permit of the use of an independent latch-keeper bolt by its insertion into the case of the lock to be caught by the tumblers and by its ejection from the case when unlocked. This latch-keeper bolt D, which 85 is clearly shown in the detail, Fig. 4, is made with hooks h h, to engage with the hooks of the tumblers b b, and in order that it may lock the latch it has formed or cast with it a hook or projection, i, adapted to guide and hold it 90 in the slot g, under the end of the latch-bar, or in connection with said bar, as clearly shown in the details, Figs. 7 and 8. It has also the provision of a latch-keeper having the bevel-slide surface k' and the keeper-shoulder k, as 95 shown in the details, Figs. 4, 6, and 8.

It having been stated that the object of the invention is to produce a combined latch and lock, it is only necessary to describe its use in the two functions.

When the device is used as a latch merely, as shown in Figs. 2, 5, and 6, the latch-keeper bolt D is inserted in the lock and held by its hooks, as shown in the detail Fig. 9. The latch as it falls in the usual manner slides over the bevel-slide k' and is caught and held by the shoulder k, as in any ordinary keeper. There are thumb-pieces e e', to operate the latch-bar from both sides, as shown in Fig. 11, through a slot in the gate or door.

When the device is to be used to lock the latch, the latch-keeper bolt D is ejected by releasing the spring-tumblers, and the latch-keeper bolt is then placed in the slot g, with its hook i under the end of the latch-bar E, as in Fig. 7, within which slot it has capacity for free movement, as described. Being thus shoved into the lock proper to engage with and be held by the hooked tumblers, and being also held in the slot g of the latch-bar, the latter and the lock proper are thereby securely locked. To unlock, it is only necessary to apply the key F to open the spring-tumblers to cause the latch-keeper bolt to be ejected by the spring m, when the bolt is again used as a latch-keeper.

At Fig. 13 there is an end view of the slotted latch-bar, showing the under recess, s, for the hook projection i of the latch-keeper bolt to slide in to connect it with the latch-bar.

I claim—

1. The combination, with a latch-bar, E, provided with a slot, g, and a spring tumbler-lock, C, of an independent latch-keeper bolt, D, provided with hook projections for engagement with said tumbler-lock and with the latch-bar, substantially as and for the purpose set forth. 35

2. The combination, with the lock spring hooked tumblers b b and a latch-bar, E, having a slot, g, of an independent latch-keeper bolt, D, formed with the hooks h h, hook projection i, and beveled shouldered keeper k k', substantially as and for the purpose set forth. 40

In testimony whereof I have hereunto set my hand in the presence of two subscribing witnesses. 45

HIRAM C. STOUFFER.
